UNITED STATES PATENT OFFICE.

AMOS H. SMITH, OF NEW YORK, N. Y.

FASTENING DEVICE FOR WINDOW-SASHES.

SPECIFICATION forming part of Letters Patent No. 635,982, dated October 31, 1899.

Application filed January 23, 1899. Serial No. 703,058. (No model.)

To all whom it may concern:

Be it known that I, AMOS H. SMITH, a citizen of the United States, residing at New York, (Brooklyn,) in the county of Kings and State of New York, have invented certain new and useful Improvements in Fastening Devices for Window-Sashes, of which the following is a full and complete specification, such as will enable those skilled in the art to which it app pertains to make and use the same.

This invention relates to fastening devices for window-sashes; and the object thereof is to provide an improved fastening device for this purpose which is designed to lock the sashes together when in their normal or closed position and also to draw the bottom of the upper sash and the top of the lower sash together, so as to prevent rattling and shaking of the sashes.

The invention is fully disclosed in the following specification, of which the accompanying drawings form a part, in which—

Figure 1 is a plan view of the bottom part of the upper sash and the upper part of the lower sash and showing my improved sash-lock or fastening device connected therewith; Fig. 2, a section on the line 2 2 of Fig. 1; Fig. 3, a front view of the device as shown in Fig. 1; Fig. 4, a section on the line 4 4 of Fig. 1, and Fig. 5 a section on the line 5 5 of Fig. 1.

In the drawings forming part of this specification the separate parts of my improvement are designated by the same numerals of reference in each of the views, and in said drawings I have shown at 7 the upper part of the lower sash and at 8 the bottom of the upper sash, and in the practice of my invention I provide a fastening device for the purpose herein described, comprising two separate parts 9 and 10, the first of which is designed to be connected with the bottom part of the upper sash and the second with the top of the lower sash.

The part 9, which is connected with the bottom of the upper sash, consists of a plate provided with a central raised casing 11, which is open at the front and provided at one side with a pin 12.

The part 10, which is designed to be secured to the top of the lower sash, consists of a plate provided with a central transverse raised casing 13, the rear end of which is

open, and which is provided in the top and adjacent to one side with a longitudinal slot 14, and in the front end thereof with a vertical slot 15, and in the right-hand side thereof with a longitudinal slot 16.

Mounted in the transverse casing 13 is a bolt 17, which is adapted to be projected backwardly or outwardly into the casing 11 by a spring 18, and the front end of the bolt 17 is cut away on the under side to form a recess 19, in which said spring is placed, and pivotally connected with said bolt at 20 is a lever-bar 21, which projects through the slot or opening 15 in the front end of the casing 13 and is provided with a ring or handle 22, and said lever-bar 21 is provided rearwardly of its front end with a downwardly-directed shoulder or projection 23, and by pulling said lever-bar outwardly until the rear end of the shoulder or projection 23 engages with the bottom of the slot or opening 16 the bolt 17 will be withdrawn within the casing 13, as shown in said figure, and by raising said lever-bar until the shoulder or projection 23 is disconnected from the bottom of said slot or opening the bolt 17 will be projected into the casing 11, as shown in Fig. 4, and the sashes will be locked together.

The bolt 17 is cut away longitudinally at its top, as shown at 24, and passing through the top of the casing 13 is a pin 25, on which is pivoted a backwardly-directed curved arm 26, which operates in the slot or opening 14, and is provided at its rear end with a cross-head 27 and with a downwardly-directed curved finger 28, and the bolt 17 is provided, on the left-hand side thereof, with a pin 29, with which said finger is adapted to engage when the bolt 17 is drawn forwardly and disconnected from the casing 11, as shown in Fig. 5.

Pivoted to the right-hand side of the casing 13 and at the bottom thereof, as shown at 30 in Fig. 2, is a dog 31, provided with a downwardly and backwardly directed finger 32 and in the body portion thereof with an inclined slot 33, and passing through the slot 33 is a pin 34, which passes through the slot or opening 16 in the side of the casing 13 and into the bolt 17, with which it is connected, and the finger 32 of the dog 31 is adapted to engage with the pin 12, secured to the casing

11 when the sashes are locked together, as shown in Fig. 2.

The arm 26 is extended below its pivot 25 in the form of a segmental or cam-shaped projection 35, which upon the movement of the arm 26 as the weight 27 drops engages the inner or rear end of the lever 21.

The normal position of the parts when the sashes are locked together is shown in Fig. 4, and in order to operate the device so that the sashes may be adjusted or the upper sash lowered or the lower sash raised the bolt 17 is drawn outwardly by the lever-bar 21, as shown in Fig. 5, and held in such position by said lever, the shoulder or projection 23 engaging with the bottom of the slot or opening 16, and as the windows, or either of them, are opened the weight 27 and the arm 26 drop downwardly, whereupon the finger 28 of said arm engages with the pin 29 and also holds the bolt in the withdrawn position, or that shown in Fig. 5. As the weight commences to drop, the projection 35 on the lower end of the arm 26 strikes the inner or rear end of the lever 21, depressing the same and correspondingly raising the forward end of said lever, thereby releasing it from engagement with the lower edge of the slot 16, whereupon the said lever 21 has no further locking action or hold upon the retracted bolt 17, which is, however, held in such retracted position by engagement of the curved finger 28 with the pin 29 of said bolt, it being noted that this finger engages said pin before the projection 35 releases the lever 21, and so long as the weight remains down the finger 28 will hold the bolt against projection. If now it is desired to lock the sashes together, the lower sash is moved downwardly or the upper sash upwardly. In this operation the head or weight 27 of the arm 26 strikes the top of the casing 11 and is forced upwardly, releasing the pin 29 from the finger 28, and the front end of the lever-bar 21 being already raised or released the spring 19 throws the bolt 17 backwardly into the casing 11 and the sashes are locked together, and at the same time the pin 34, which is secured to the bolt 17, operates the dog 31 and causes the finger 32 thereof to engage with the pin 12, secured to the side of the casing 11, and draws the sashes together, as will be readily understood.

My improved sash-lock or fastening device is simple in construction and operation and perfectly adapted to accomplish the result for which it is intended and it will be apparent that changes in and modifications of the construction described may be made without departing from the spirit of my invention or sacrificing its advantages.

Having fully described my invention, I claim as new and desire to secure by Letters Patent—

1. A sash-lock comprising two casings, one of which is adapted to be secured to the lower, and the other to the upper sash, the adjacent ends of which are open, a normally-projected

bolt mounted in the casing which is adapted to be secured to the lower sash, means for retracting said bolt and for holding it temporarily in a retracted position, means for automatically releasing the temporary retracting means and at the same time engaging the bolt to hold it while retracted, the same embodying a movable projecting part, which, when the windows are closed, will be actuated to entirely release the bolt and permit the same to project operatively, substantially as shown and described.

2. A sash-lock, comprising two parts, one of which is designed to be secured to the upper and the other to the lower sash, that part which is designed to be secured to the upper sash being provided with a central raised casing which opens forwardly, and that part which is designed to be secured to the lower sash being provided with a central transverse raised casing which opens backwardly, a bolt mounted in said casing and provided with a spring for forcing it backwardly, a lever-bar pivotally connected with said bolt and projecting through a slot or opening in the front end of said casing, and by which said bolt may be drawn forwardly into said casing and locked therein, said casing being also provided with a curved pivoted arm which projects through a slot in the top thereof, and which is adapted to be operated by the casing of the upper sash, said arm being also provided at its rear end with a transverse head, and with a downwardly-directed finger, and said bolt with a pin with which said arm is adapted to engage, substantially as shown and described.

3. A sash-lock, comprising a casing 11 which is adapted to be secured to the upper sash and which opens forwardly, and a casing 13 which is adapted to be secured to the lower sash and which opens backwardly, a spring-operated bolt 17 mounted in said casing 13, a lever-bar 21 connected with said bolt and projected through the front end of the casing 13, a curved arm 26 pivoted in the top of said casing and provided at its rear end with a cross-head, and a downwardly-directed finger 28, a pin 29 connected with said bolt in connection with which said finger operates, said casing 13 being also provided with a pivoted dog 31 having a slot 33, and said bolt with a pin 34 which projects through the side of the casing 13, and through the slot 33, and said dog 31 being also provided with a finger 32, and the casing 11 with a pin 12 with which said finger engages, substantially as shown and described.

4. In a sash-lock, the combination of casings adapted to be secured respectively to the upper and the lower sash, a bolt or lock mechanism for securing said sashes through the medium of said casings, means for retracting and for automatically releasing the bolt when the sashes are closed, and an auxiliary projecting portion or dog movably mounted in the casing of the lower sash and

adapted to operate in connection with the bolt-releasing mechanism, said dog being provided with a projecting finger, and the casing of the upper sash being provided with a 5 projection over which said finger is adapted to engage or hook to further secure the sash, substantially as shown and described.

5. A sash-lock, comprising a casing secured to the upper sash, and a casing secured to the 10 lower sash, the adjacent ends of said casings being open, a spring-operated bolt mounted in the casing secured to the lower sash and adapted to be projected into the casing secured to the upper sash, a lever-bar connected with 15 said bolt and projecting through the outer or front end of the casing in which it is mounted, a curved arm pivoted in the top of said casing and projecting backwardly and provided with a finger which engages with a pin 20 secured to said bolt, said casing being also provided with a pivoted dog which is in operative connection with said bolt and adapted to engage a pin secured to the casing connected with the upper sash, substantially as 25 shown and described.

6. A sash-lock, comprising two casings, one

of which is adapted to be secured to the lower and the other to the upper sash, and the adjacent ends of which are open, a spring-operated bolt mounted in the casing which is 30 adapted to be secured to the lower sash, a lever pivotally connected therewith and projecting from said casing and adapted to hold said bolt in a retracted position, and means for automatically releasing said lever when 35 the sashes are closed, consisting of a normally-depressed arm mounted in said casing and projecting backwardly therefrom, whereby said arm is raised as the sashes are closed, said arm being provided with means for releasing the bolt-retracting lever, and with means for holding said bolt in the retracted position, substantially as shown and described.

In testimony that I claim the foregoing as 45 my invention I have signed my name, in presence of the subscribing witnesses, this 20th day of January, 1899.

AMOS H. SMITH.
